No. 813,421.

PATENTED FEB. 27, 1906.

W. J. HIGMAN.
NON-REFILLABLE BOTTLE.
APPLICATION FILED JUNE 19, 1905.

UNITED STATES PATENT OFFICE.

WILLIAM J. HIGMAN, OF DENVER, COLORADO.

NON-REFILLABLE BOTTLE.

No. 813,421.

Specification of Letters Patent.

Patented Feb. 27, 1906.

Application filed June 19, 1905. Serial No. 265,951.

To all whom it may concern:

Be it known that I, WILLIAM J. HIGMAN, a citizen of the United States of America, residing in the city and county of Denver and 5 State of Colorado, have invented a new and useful Non-Refillable Bottle, of which the following is a specification.

My invention relates to bottles of that class which are especially designed to prevent re- 10 filling by an unauthorized person with an inferior grade or a spurious liquid after a part or the whole of the original contents shall have been emptied from bottle or package.

The object which I have in view is the pro- 15 vision of a simple and inexpensive construction which allows the bottle or package to be originally filled in an easy manner, after which the several parts may be quickly as- 20 sembed to prevent access being obtained to them for subsequent removal and at the 25 same time allow the liquid to be easily and readily decanted. I attain these objects by the mechanism illustrated in the accompanying drawings, in which—

Figure 1 is a vertical sectional view of my 30 improved non-refillable bottle. Fig. 2 is a plan view of the stopper-holding cap. Fig. 3 is a plan view of the sleeve which fits in the neck of the bottle. Fig. 4 is a perspective 35 view of the valve-cover. Fig. 5 is a top plan view of the same. Fig. 6 is a bottom plan view thereof. Fig. 7 is a plan view of the cap upon which the valve rests, and Fig. 8 is a horizontal sectional view on line 77 of Fig. 1.

Similar numerals of reference refer to simi- 40 lar parts throughout the several views.

Referring to the drawings, in which I have 45 illustrated only the top portion and the neck and entrance of a bottle, together with such 50 elements as comprise my invention, numeral 1 designates a fragment of the top portion of a bottle; 2, its neck portion, which is provided with a mouth 3. At the entrance to the mouth a short counterbore 4 is formed. In 55 the peripheral surface of the counterbore I form a circumferential recess 5, which I term a "keyway." In the mouth of the neck of the bottle I place a sleeve 6, which fits loosely therein and is provided with an 60 annular lip 7 at its top end which fits the counterbore 4 and rests on the shoulder 8, formed between the two apertures 3 and 4. This sleeve is provided with a bottom 9, in 65 which an axial aperture 10 is formed. The lower end of the sleeve is provided with a circumferential groove 6^a, in which a rubber

washer 6^b is placed, which is adapted to bear resiliently against the inner peripheral surface of the neck with pressure enough to prevent the liquid going by it up into the 60 neck of the bottle. In the lower part of the interior of the sleeve a float-chamber 10^a is formed, in which several introverted guard-ribs 11 are formed, which extend from the edge of the aperture in the bottom of the 65 sleeve, from which they curve backwardly enough up in the sleeve to allow a ball-shaped float 11^a, of rubber or other suitable material, to be inserted in the sleeve and to rest loosely between the flukes and against the 70 aperture in the bottom of the float-chamber and raise the float from its seat a sufficient distance to permit the contents of the bottle to be easily poured out of the bottle past it. These guard-lips are of even length, and on 75 top of them I set a cap 12, the inside of which is provided with a plurality of introverted guard-lips 13, that extend from the inner periphery of the cap to near but not quite to the center at their lower ends, which extend 80 from the lower edge of the cap flush or even with it and rest directly on the flukes 11 of the float-chamber, which are adapted to confine the float to the center of the chamber and at the same time to form passages for the 85 liquid around it. From their lower points, however, these flukes slope backward to the inner surface of the cap and join the cap on the edge of an aperture 14, formed through its top surface. These flukes also act to 90 form passages for the liquid, and also to prevent the float from approaching too near the liquid-outlet aperture 14 in the cap. The top of this cap is level, and on it I place a conical valve 15, which is preferably made 95 of an angle of forty-six degrees, although the valve may be made of any other angle, if desired. Over this conical valve I place a spider-shaped member 16, which I term the "valve-cover," which comprises a central hub portion 100 17, from which a plurality of guard-wings 18 radiate at equal distances apart around its surface. I preferably use four of these wings, and they are of equal length and fit loosely inside of the sleeve and rest on top of the cap 105 12, and through the center of the hub a small aperture 18^a is formed, that registers directly over the apex of the conical valve. The lower end of this spider-shaped valve-cover is provided with a concaved recess, and the ends 110 of the four wings which rest on the cap 12 extend at an upward level of slightly less de-

gree than the slope or level of the conical valve from the cap on which they rest to the top of the concaved recess, and between these four guard-wings I form a plurality of short straight guard-wings 18^A, which extend from the edge of the concaved recess to its apex, and they are of the same angle as the long ribs 18. The angle of the conical valve is preferably forty-six degrees, while I preferably make the slope of the inner edges of these valve guard-wings forty-five degrees, as they will keep the valve in position to cover the outlet-aperture in the float-cap when bottle is standing on its bottom or is inclined below a horizontal angle not greater than forty-five degrees, but when turned to an angle of forty-six degrees they allow the valve to open to its fullest capacity, and in order to do this I make these guard-wings with enough larger conical space between them to permit the valve to move operatively on its seat in the conical space formed by them. The wings of the valve-cap are of even height and extend above the hub portion to allow ample spaces between them for the liquid in the bottle to run out over the hub, and on top of the wings I place a stopper-holding cap 19 on top of a flexible washer 19^A. This cap consists of a stem part having an enlarged disk-shaped base which fits closely but loosely in the counterbored entrance to the neck of the bottle and rests on top of the wings of the valve-cover. The periphery of the disk portion of this stopper-holder is provided with a circumferential keyway 20, that registers opposite the keyway 5 in the neck of the bottle, and on opposite sides of the disk I form in its upper edge two small grooves 21 and 22, that extend into its keyway, as shown in Fig. 2. The stem portion of the stopper-cap is provided with an axial aperture of two diameters 23 and 24, the smaller of which is in its bottom and forms the liquid-passage from the bottle, while the larger aperture is outwardly tapered as made to receive a stopper. In the keyways of the neck and stopper-holder I place two keys 25. These keys are made in the form of a crescent and comprise a two-winged spring-key. (See Fig. 8.) These springs may be made of any suitable spring metal or of any suitable material. The wings 26 and 27 are formed to be resiliently bent back against the ends 28 and 29 of the key, as the center of the key is of the same thickness as the ends; but the spring-wings are adapted to normally stand out from the body of the key, but are compressed against the ends when the keys are inserted in the keyways of the neck and stopper-holding cap.

The operation is as follows: The bottle is filled before my non-refilling device is put into it; but after it is filled the sleeve, with its washer 6^B, is first pressed into the neck of the bottle. The float is then placed in the

float-chamber of the sleeve. The float-cap is then placed over the float. Then the conical valve is placed on the cap and the valve-cover is placed over the valve, and then the spring-keys are placed in the keyways of the stopper-cap. It is placed in the counterbore of the neck of the bottle on top of the valve-cover, and as it is pressed into place the two springs, which are held on opposite sides of the keyway of the stopper-cap with the fingers and pressed into the keyway until they are pressed into the neck of the bottle, fly outward into the keyway of the neck of the bottle when the two keyways register opposite each other. These spring-keys are made enough narrower than the width of the keyway to permit them to easily expand from the cap into the keyway of the neck of the bottle. A suitable cement is then inserted in the keyways through the grooves 21 and 22, and the device is sealed. A stopper 30 is then placed in the stopper-cap. To pour out the liquid contents of a bottle equipped with my non-refillable device, first remove the stopper, then turn the bottle-neck downward substantially at or below an angle of forty-five degrees, when the liquid will flow out freely. In case the conical valve should stick from long standing insert a wire through the aperture 18^A in its cover, which will strip the valve on one side of its apex and move it to one side. Then the bottle is tilted to pour out its contents, the float rolls against its cap, and the conical valve slides to the lowest side of its seat on the cap and against its guard-lips, and the liquid flows past the float through the flukes of the float-cap and through its central aperture past the conical valve and between the flukes of the valve-cover around its hub portion and over its top out through the stopper-cap. The construction of the valve-cover is such that it is impossible to insert a wire or anything around the valve-cover and in any way lift or move or manipulate the conical valve to refill the bottle, while the proportionate dimensions of the base of the conical valve and the liquid-discharge aperture 14 are such that the valve can slide to any way and come in contact with its guard-wings and still cover the discharge-outlet 14, and should an attempt be made to force liquid into it by tipping the bottle upside down the float will rise up against its seat and prevent the entrance of any liquid into the bottle.

My non-refillable bottle is simple in construction, its parts are few and are easily made and quickly assembled, and the form of the neck of the bottle is also very simple and easy to make.

Having described my invention, what I claim as new, and desire to secure by Letters Patent, is—

1. In a non-refillable bottle, the combination with the bottle having a mouth, of the

sleeve, secured in said mouth, having a liquid-outlet, a float arranged to control said outlet, introverted flukes in said sleeve arranged to form liquid-passages around said float, and a 5 fluted cap having a liquid-outlet arranged in said sleeve to confine the operative movement of said float.

2. In a non-refillable bottle, the combination with the bottle, of the sleeve, the float 10 adapted to control the outlet of the bottle, and the float-cap, having a liquid-outlet, with the conical valve, mounted on said cap, to control said liquid-outlet, a spider-cover in said sleeve over said valve arranged to control 15 its operative movement, and means for confining said spider in said sleeve, as set forth.

3. In a non-refillable bottle, the combination of the bottle with the sleeve, the float 20 adapted to control the outlet of the bottle, the float-cap, the conical valve, and the spider having a conical recess of greater angle, and area, than said valve, arranged to fit over said valve, with clearance-space enough 25 to allow said valve operative movement within said spider's conical recess, arms on said spider arranged to form liquid-passages around said valve, a hub portion to said spider having a small axial aperture through 30 it, and means including a stopper-holding cap arranged to be keyed in said bottle to confine said spider in operative relation to said valve, as set forth.

4. In a non-refillable bottle, the combination 35 of the bottle having a neck having a mouth provided with a counterbore at its entrance, and having a circumferential keyway, with the sleeve seated in said counterbore and mouth, the float adapted to control the 40 outlet of the bottle, the float-cap, and valve-seat, the conical valve, and the valve-cover in said sleeve, the stopper-cap, having a flange portion fitting the counterbore in said mouth, and provided with a circumferential 45 keyway arranged to register opposite the keyway of said bottle's counterbore, the keys having spring-wings and arranged to be sprung into said keyway, as set forth.

5. In a non-refillable bottle, the combination 50 with the bottle having a mouth, provided with a counterbore having a circumferential keyway, of a stopper-receiving cap, adapted to fit in said counterbore and containing a liquid-outlet, said stopper-cap having a circumferential keyway arranged to 55 register with said keyway, in said counterbore, and a key having two spring-wings arranged and adapted to be inserted in said registering keyways and lock said stopper- 60 cap to said bottle, as set forth.

6. In a non-refillable bottle, the combination 65 with the bottle having a mouth, provided with a counterbore having a circumferential keyway, of a stopper-receiving cap, adapted to fit in said counterbore and hav-

ing a liquid-outlet, said stopper-cap having a circumferential keyway arranged to register with said keyway, in said counterbore, and a key having two spring-wings arranged and adapted to be inserted in said registering keyways and lock said stopper-cap to said bottle, 70 said stopper-cap being provided with grooves in its peripheral edge leading into said keyways arranged and adapted to conduct a suitable cement into said keyways, as set forth. 75

7. In a non-refillable bottle, the combination of the bottle having a neck having a mouth provided with a counterbore, having a keyway, a stopper-cap filling said counterbore, having a keyway registering with the 80 keyway in said counterbore, and keys, comprising crescent-shaped keys having spring-blades adapted to be compressed and placed in the keyway of said caps, while inserting said cap in said counterbore, and adapted to 85 expand into the keyway of said counterbore when said keyways register with each other after said cap is inserted in its operative position in said counterbore, as set forth.

8. In a non-refillable bottle, the combination 90 with a bottle provided with a neck having a mouth having a counterbore, keys in said counterbore, and a stopper-cap secured to said mouth by said keys, of a sleeve in said mouth, having a float-chamber, having a liquid-outlet aperture, a float in said float-chamber, a cap arranged to define the operative movement of said float, provided with an outlet-aperture, and a valve operatively arranged to control the outlet-aperture of said 95 cap, substantially as described. 100

9. In a non-refillable bottle, the combination 105 with the neck provided with a mouth and a counterbore at the entrance to the mouth, the sleeve, the float adapted to control the outlet of the bottle, the cap for defining the movement of said float, said sleeve and cap being provided with liquid-outlet apertures, with a conical valve seated on said float-cap, a winged-valve-holding hub arranged to confine said valve in operative relation to its seat, a stopper-cap in the mouth of said bottle, and means, including keys, for securing said stopper-cap in the mouth of said bottle, substantially as described. 110 115

10. In a non-refillable bottle, the combination 120 with the bottle, provided with a neck and mouth and having a circumferential keyway in the entrance to its mouth, a sleeve secured in the mouth of said bottle, provided with a liquid-outlet aperture and a float-chamber in its bottom, a circumferential row of introverted flukes in said float-chamber around its periphery, a float in the center of said flukes arranged to control said liquid-outlet, a cap 125 containing a liquid-outlet aperture seated on said flukes in said float-chamber, a circumferential row of flukes in said cap adapted to prevent said float from approaching too near said cap-outlet, and to provide passages for said 130

liquid around said float, a conical valve seated on said cap over said liquid-outlet, a spider-block arranged over said valve containing a beveled recess defined by the inner 5 lower edges of said spider's guard-arms, and arranged and adapted to permit operative movement of said valve on its seat, said cap being provided with a small aperture registering opposite the apex of said valve, and 10 means, including a stopper-receiving cap, secured in the mouth of said bottle, for confining said spider in operative relation to said valve, substantially as described.

11. In a non-refillable bottle, the combination of a bottle, a sleeve having a liquid-outlet secured in the mouth of said bottle, said sleeve 15 also having a float-chamber, a float contained therein; a cap and flukes arranged to define the movement of float, and provided with a 20 liquid-discharge aperture, a conical valve seated on said cap to control its liquid-outlet aperture, a spider arranged to operatively confine said valve to its seat, and means, in-

cluding a stopper-holding cap and a keyway formed partially in said stopper-cap and in 25 said bottle and suitable keys, for securing said spider in operative valve-controlling relation to said valve, substantially as described.

12. In a non-refillable bottle, the combination of the bottle having a keyway with the 30 sleeve having a liquid-outlet aperture, the float in said sleeve arranged to control said outlet-aperture, and the float-cap having a liquid-outlet aperture, with the conical valve, the valve-confining spider, and the stopper- 35 cap, having a keyway, registering opposite the keyway in said bottle, and the spring-keys arranged and adapted to said keyways, as set forth.

In testimony whereof I affix my signature 40 in presence of two witnesses.

WILLIAM J. HIGMAN.
